UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

GUN-CARRIAGE.

1,266,924.

Specification of Letters Patent. Patented May 21, 1918.

Application filed September 28, 1915. Serial No. 53,155.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Gun-Carriages, of which the following is a specification.

This invention relates to a cycle side car adapted to serve as a carriage for a breech loading gun of the Maxim or other type.

According to this invention the parts of the side car are so constructed and arranged that the gun and gunner's seat occupy such a position relative to each other, that the gun can be operated under ordinary circumstances without its being necessary for the gunner to leave his seat. The seat is preferably arranged contiguous to the side car axle and the training pivot of the gun is carried by a suitable framework (forming part of the side car) in front of and at a convenient height above the gunner's seat with the muzzle of the gun pointing in the direction of movement of the cycle and side car. The gun may also be so mounted on the framework that it can be swung horizontally about its pivot through an angle of 180 degrees in which position the breech end of the gun can be depressed for enabling the gun to be used against air-craft; in this case the gunner would have to leave his seat in order to operate the gun.

In order that the said invention may be clearly understood and readily carried into effect, we will describe the same more fully with reference to the accompanying drawings, in which:

Figures 1, 2 and 3 are respectively a front elevation a side elevation and a plan showing a side car (attached to a motor cycle) constructed in accordance with our invention.

Fig. 4 is a side elevation of an ammunition container carried by the side car and having an improved device for retaining the ammunition boxes in position, and Fig. 5 is a detail.

The gun shown in the drawings is of the Maxim type and its crosshead c is carried by an upper carriage c' whose training pivot is supported in a socket C . This socket forms the junction piece of two tubes $C' C'$

connected at their rear ends to the side car axle. The axle thus constitutes the base and the socket the apex of a triangular structure. Arranged across the said two tubes is a training arc C^2 for the reception of a rearward extension of the upper carriage c' to which is connected the elevating gear preferably comprising a screw and hand wheel as shown. The upper carriage and the crosshead are normally connected together but when the gun is to be used for high angle firing these parts are disconnected so that the gun together with the cross head can be swung horizontally through an angle of 180 degrees as above stated; the elevating gear is disconnected from the gun before this operation is effected. When the gun is in this position the breech end can be depressed as shown by chain lines in Fig. 2 for high angle firing.

The cartridge belt box C^x may be carried by the mechanism casing of the gun as shown or by the framework of the side car and a detachable shield D moving with the gun in elevation and training may be provided; additional shields D', D'' may be detachably carried by the front portion of the framework for protecting the side car and the gunner's body.

The side car axle may as shown carry a spring supported frame E containing ammunition boxes, one or more water tanks for supplying the water jacket of the gun and receptacles for spare parts. These boxes and other receptacles may be retained in position by a strap E^x (Fig. 3) or by a transverse bar E' (Fig. 4) carried by arms E^2 pivoted at e^2 to the rear portion of the spring frame. The bar is held in its operative position by a spring controlled clip or catch E^3 which can be displaced to enable the bar to be moved downward about its pivots and thereby liberate the boxes which can then be drawn rearwardly from the spring frame E . The latter also serves to carry the shields when they are detached, and carries two blocks (one of which is shown at E^4 in Fig. 4) having suitable grooves for the reception of the legs of a detachable tripod mounting for the gun, which can be employed when the gun is removed from its mounting on the gun carriage. The spring supported frame for the ammunition carrier illustrated at Fig. 4 forms no part of the present invention. The

100 105 110

framework of the side car may comprise in addition to the triangular structure above referred to, a second or lower triangular structure F, F, F' also having the axle B 5 as its base. The first mentioned structure is inclined forwardly and upwardly while the lower structure is inclined downwardly in Figs. 1 to 3 and forwardly and downwardly in Fig. 4; the apex or junction piece F' of 10 the lower structure is connected to the socket C of the other structure by a member F². The said junction piece F' may act as a support for the gunner's seat or, as illustrated more particularly at Fig. 5 the gunner's seat 15 A may be carried on the member F². It will be observed that the seat A to which the back rest F⁴ is secured, is itself connected to the member F² by the seat bracket F³ which latter is secured to the member F² 20 in any suitable manner. The tubes C' C' may carry pivoted struts c², c² connected by a transverse rod c³, for assisting in supporting the socket c² when the side car is stationary and the gun is firing at high angles of 25 elevation; these struts are however not necessary and may be dispensed with.

What we claim and desire to secure by Letters Patent of the United States is:—

1. The combination with a motor cycle, 30 controlled by a driver, of a side car comprising an upwardly inclined triangulated framework, an axle forming part of said triangulated framework, a road wheel carried by said axle, means for connecting the side car to the motor cycle, a gunner's seat on said framework arranged contiguous to the side car axle, a gun supporting member connected to the apex of said upwardly inclined triangulated framework and arranged 35 in front of and at a convenient height above the gunner's seat, and a gun pivotally supported on said gun supporting member with its muzzle pointing in the direction of movement of the side car for the 40 purposes set forth.

2. The combination with a motor cycle controlled by a driver, of a side car comprising a framework, an axle connected to said framework, a road wheel carried by said 45 axle, means for connecting the side car to

the motor cycle, a gunner's seat on said framework arranged contiguous to the side car axle, a gun supporting member connected to said framework and arranged in front of and at a convenient height above the gunner's seat, a gun pivotally supported on said gun supporting member with its muzzle normally pointing in the direction of movement of the side car, and means which are so constructed that when required the gun 55 can be swung horizontally through an angle of 180 degrees about said gun supporting member in which position the breech end of the gun can be depressed through a large angle of elevation for enabling the gun to 60 be used against aircraft.

3. The combination with a motor cycle controlled by a driver, of a side car comprising a framework, an axle connected to said framework, a road wheel carried by 70 said axle, means for connecting the side car to the motor cycle, a gunner's seat on said framework arranged contiguous to the side car axle, a gun supporting member connected to said framework and arranged in front 75 of and at a convenient height above the gunner's seat, means for supporting a gun on said gun supporting member so that the gun is capable of swinging horizontally through an angle of 180 degrees in which position 80 the breech end of the gun can be depressed through a large angle of elevation for enabling the gun to be used against aircraft, together with a frame on the side car framework for carrying ammunition boxes. 85

4. A cycle side car serving as a gun mounting, having a frame for carrying ammunition boxes and means for retaining said boxes in position on the frame comprising a transverse member, arms pivoted to said frame carrying said transverse member, and a catch for holding said transverse member in its operative position.

In testimony whereof we affix our signatures in the presence of two witnesses.

ARTHUR TREVOR DAWSON.
GEORGE THOMAS BUCKHAM.
